UNITED STATES PATENT OFFICE.

HARVEY W. BAILEY, OF PORTLAND, OREGON, ASSIGNOR TO HARVEY BAILEY, OF PORTLAND, OREGON.

CONCENTRATOR.

1,111,687.

Specification of Letters Patent. Patented Sept. 22, 1914.

Application filed November 15, 1913. Serial No. 801,188.

To all whom it may concern:

Be it known that I, HARVEY W. BAILEY, a citizen of the United States, residing at Portland, in the county of Multnomah and State of Oregon, have invented certain new and useful Improvements in Concentrators, of which the following is a specification.

This invention relates to concentrators, and has for its object to provide a series of 10 rifle boxes in such relation to each other that the material to be concentrated will be graded and will be caused to gravitate over the series, dropping the heavier particles into the boxes, and allowing the lighter particles which possess no value to be shunted from the raceway and disposed of.

A further object is to provide a plurality of series of riffles in such relation that the gravel or other material being concentrated 20 will gravitate over each series successively to deposit its value bearing content into the riffle boxes, with means at intervals along the raceway for shunting the barren portions of rock from the device.

25 Other objects will appear by a reference to the specification describing my invention and to the drawings illustrating same, in which—

Figure 1 is a side elevation of the complete device, partly in section. Fig. 2 is a front elevation of said device, with hose and valves removed. Fig. 3 is a plan view of a riffle box, with the median portion broken away. Fig. 4 shows an end view of the 30 riffle bars. Fig. 5 is a sectional elevation taken on the line C—C of Fig. 3. Fig. 6 is a front elevation of a riffle box. Fig. 7 is a sectional elevation taken on the line A—A of Fig. 1. Fig. 8 is a sectional elevation on 35 the line B—B of Fig. 7. Fig. 9 is a detail end view of an air pump, with the cover removed. Fig. 10 is a sectional elevation on the line D of Fig. 9. Fig. 11 is an end view of a slide plate. Fig. 12 shows the 40 method of attaching the slide plate to boxes.

Describing the drawings in detail, 1 designates the hopper of my improved concentrator, which is made preferably in one with the casing 55 and formed of sheet metal, 50 with a series of protrusions or wings 1^a at each side to form a two-part raceway in each of which parts is inclosed a series of zig-zag sections containing the outwardly inclined nugget boxes 45 into and over

which the material passes and falls upon 55 the inwardly inclined grizzlies 45^a supported upon brackets 45^b, each grizzly being provided with a series of openings 47 to permit the smaller particles to gravitate onto the riffle boxes 23 as they return to the 60 central portion of the casing 55, where the waste will fall, at the lower end of each grizzly, into the pocket screen 54, which permits the small particles to sift through, to 65 gravitate into and through the succeeding race ways in the manner just above described. The sections are pivotally supported by means of pivot pins 60, upon the risers 10. The coarser materials will gravitate over the edge of the pocket screen 54 70 and descend through the central portion into the hopper 64, whence it is discharged.

The device is mounted upon standards 10 which rise from a suitable base 17 and to the tops of which are secured brackets 5 in 75 which is mounted a shaft 20. Upon each end of said shaft 20 is mounted a hanger 3, the shank 3^a of which is mounted in the bearing 2, which is secured to the U-beam 4, suitably supported from a frame work. 80 From the U-beams, at each side a bracket 6, depends to support between the upper boxes 45 and the grizzlies beneath, a shaft 21, carrying a drive pulley 22. This shaft passes through the large openings in the 85 risers 10. Upon this shaft at a suitable point is fixed an eccentric 19 mounted in the strap 19^a, to which is connected the rod 48, which in turn is mounted upon the shaft 46. This shaft is fixed in the casing 55. 90

At a suitable point upon the main frame, in line with shaft 21, is placed an air pump 7 which is directly connected with the reservoirs 8, by means of the outlet 9 and laterals 52, suitable bearings being formed in the 95 pump casing for said shaft. Upon the shaft 21, within the pump casing 7 is fixed a disk 72 of smaller diameter than the casing; and at opposing sides in the disk are mounted slide vanes 70 in grooves 71, which vanes are 100 normally held outwardly by means of compression springs 77 in the recess 79, formed in the tongues 70^a of the valves, which tongues slide in the recesses 80 so as to yieldably bear against the wall of the pump as 105 the disk is revolved with its shaft. The lower series of riffle boxes, grizzlies, etc. are carried upon cross bars 27, which in the

upper portion of each wing, are carried upon sections 11 and 12 to the body of the casing, upon the pins 60 and at the outer ends they connect by means of hinges 53, with the co-acting lower sections 14 and 13 respectively, which connect at their inner ends by means of a sliding pivot 63 with the slide block 65 movably mounted in the enlarged portion 10^a of the standard 10. Transversely through the enlarged portions 10^a is mounted a shaft 15 carrying a worm gear 16, at each end portion, which meshes with worm gear 67 fixed upon screw shaft 66 which engages by screw thread connection with slide block 65. The lower end 68 of shaft 66 is sustained in a suitable bearing in the portion 10^a; and by means of the crank 18 the said brackets may be adjusted to vary the inclination of the riffles, etc. carried in the hinged sections of the race ways. At suitable intervals are disposed upper and lower bars 27 arranged transversely in pairs along each of the inclines, each of said bars being provided at one or both lateral faces with a longitudinal slot 27^a near its inner face adapted to receive the correspondingly formed flanges 23^a of boxes 23, 24 and 45. At what may be termed the rear ends of said bars are formed stops 34. In each of the boxes 23 is disposed a series 30 of riffles 32 mounted upon bearings 32^b. Each bearing shaft at what may be termed the front end of the box is extended and carries a segment worm gear 29 which meshes with gear shaft 30 mounted in bearings 44, 35 and operable by means of hand wheel 31, for rocking said riffles upon their bearings. Each of said riffles is approximately triangular in cross section, with a front face provided with longitudinal scores 32^a which serve to intercept and trap such concentrates as may be blown from the box below, where they will accumulate until their weight will carry them downward against the current of air. The uppermost face 32^c is made in substantially circular form, over which the concentrates will settle presenting their flat sides thereto as seen at 45^b, so that the smaller areas will be presented against blasts of air issuing from the box into which they will 40 descend. The third and lower face 32^d is extended rearwardly from the pivot point to meet the rear edge of the face 32^c, whereby as the riffles are rocked to the rear the spaces between the riffles will be enlarged, and when 45 they are rocked forwardly said spaces will be decreased. These movements change the positions of the faces of the riffles for controlling the air currents, to aid in trapping the concentrates.

60 In the rear end of each box is a headed lug 33 to which may be attached the catch 78^a of the slide plate 78, so that as the box is withdrawn to be emptied, or for other purposes, the plate will be drawn into the grooves 27^a; 65 and upon the disengagement of the box from

the bars it will drop from the catch on the slide.

In the upper bars 27 of each incline is similarly mounted in inverted position a box 24 corresponding in size and shape to each 70 of the boxes 23; and in each of these boxes 24 is arranged in staggered relation a series of baffle plates 39, the edges being provided with a flange 39^a. The lower faces of these plates may have a facing of cocoa matting, 75 carpet or other material 41, adapted to collect concentrates carried in the air currents, which escape through the opening 40, into the carrier 81 which connects with hose 82 leading to outlet 83 in the discharge outlet 80 of the casing 55.

In operating the machine, the gravel will be fed into the hopper 1 whence it will gravitate into the nugget boxes at each side. Power will be applied through the pulley 22 85 to rotate the shaft 21 and by means of the eccentric 19 a vibratory motion will be imparted to the casing, vibrating it upon its pivot 69 in the base 17, which accelerates the movement of the gravel over the nugget boxes 90 and riffles. The disk 72 being fixed upon shaft 21 revolves with it in its casing 7, creating a suction through the intake opening 75 in the stem 74, which is controlled by the screw cap 76. The air thus taken into the 95 pump is driven out through outlets 52 leading from pipe 9 controlled by closure 73, into the pipes 51 which lead to reservoirs 8 formed adjacent the wings 1^a. From these reservoirs pipes 36 controlled by stop cocks 100 50, lead to the riffle boxes 23 through the union 35 and expansion chamber 37, below the riffles 32, between which it escapes to suspend and carry upward the lighter portions of the material, and allowing the heavier 105 particles to drop into the drawer 38.

42 is a plate covering an idle riffle, for controlling the space at the front side of the box.

As the air issues from boxes 23 it passes upward through screens 24^a into the inverted boxes 24, carrying with it all light particles of concentrates and dust. These currents will be broken up as they pass between the baffle plates 39, and they will deposit the 110 heavier particles and concentrates upon said plates. This action will be facilitated by means of the dust collector 41 consisting of fabric disposed at the farther edge of each plate 39 and on the lower face of the top 24. The lighter particles will be conveyed through the pipe 81 into outlet 83, which action is augmented by an air blast issuing from nozzle 84 let into said pipe in the direction of the current and leading directly 115 120 from reservoir 8, thereby creating a partial vacuum in boxes 24.

As the casing vibrates it is obvious that the movement will be greatest in its upper portion, decreasing toward the base.

- The angle of the series of riffle boxes may be varied by means of the worm gearing mounted in the standards 10 to control the movement of the material passing over them.
- 5 Springs 57 hold in position plates 56 which are hinged at 58, to form an adjustable portion of the casing, so as to permit the adjustment of the sections 11 and 12, and 13 and 14.
- 10 By means of the structure shown the main portion of the waste material will be shunted from the race way, over the first pocket screen 54 to descend through the casing 55 to the discharge hopper 64. The remaining 15 portion of the riffles will thus be occupied with value bearing material, while the waste will be disposed of at the outset.
- Having described my invention, what I claim is—
- 20 1. A concentrator comprising a frame, a base, a pair of risers pivotally supported upon said base, a shaft mounted in said risers, hangers journaled by one end upon said shaft and by the other upon said frame, 25 a two-part race-way built upon said risers, a casing inclosing said race-way, and means for rocking the casing upon its pivotal supports.
2. A concentrator comprising a frame, a 30 base, a pair of risers pivotally supported upon said base, a shaft mounted in said risers, hangers journaled by one end upon said shaft and by the other upon said frame, a two-part race-way disposed in zig 35 zag sections built upon said risers, a casing inclosing said race-way, a power shaft mounted in the casing intermediate the sections of said race-way, an eccentric fixed upon the power shaft and means for operatively connecting it with the first mentioned shaft for vibrating the casing upon its pivotal supports.
3. A concentrator comprising a frame, a 40 base, a pair of risers pivotally supported upon said base, a shaft mounted in said risers, hangers journaled by one end upon said shaft and by the other upon said frame, a two-part race-way disposed in zig 45 zag sections built upon said risers, air-receptacles disposed along said sections, a casing inclosing said race-way, a power shaft mounted in the casing intermediate the sections of said race-way, an eccentric fixed upon the first 50 mentioned shaft, an air compressor, communicating with said receptacles and means for operatively connecting the compressor with the power shaft, whereby said casing

and race-way may be vibrated under an air pressure.

4. A concentrator comprising a frame, a 60 base, a pair of risers pivotally supported upon said base, a shaft mounted transversely in said risers, hangers journaled by one end upon said shaft and by the other upon said frame, a two-part race-way disposed in zig 65 zag sections built upon said risers, some of which being hingedly connected, a casing inclosing the race-way and conforming thereto, a power shaft mounted in the casing intermediate the sections of said race-way, 70 an eccentric fixed upon the power shaft and operatively connected with the first mentioned shaft, air-receptacles disposed along said sections, an air-compressor communicating therewith and operatively connected 75 with the power shaft, and means adjusting the hinged sections to vary their relative positions in the race-way.

5. A concentrator comprising a casing, a 80 riffle box therein adapted to receive air under pressure, means for vibrating the casing, a receptacle having an exhaust opening at one end placed in inverted position above said riffle box, and baffle plates disposed in staggered relation throughout said inverted 85 receptacle.

6. A concentrator comprising a casing, a 90 riffle box therein adapted to receive air under pressure, means for vibrating the casing, a receptacle having an exhaust opening at one end placed in inverted position above each riffle box, flanged baffle plates disposed in staggered relation throughout said inverted receptacle, a fabric facing upon each of the baffle plates, and means for exhausting 95 the air from the inverted receptacles.

7. In a riffle box, a casing, riffles comprising a series of bars, mounted eccentrically in parallel relation, each being approximately triangular in cross section, a front 100 face of each bar being adapted to stand normally in vertical position, the upper face being rounded rearwardly to the median portion, whence the lower side continues to the bottom of the front face, a series of 105 scores being formed lengthwise in the front face of each bar, and means for rocking the bars to vary the spaces between them.

In testimony whereof, I affix my signature in the presence of two witnesses.

HARVEY W. BAILEY.
